(57) **CLAIM**

The ornamental design for a handbag, as shown and described.

DESCRIPTION

FIG. 1 is a front and left side view of a handbag showing a first embodiment of my new ornamental design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front view thereof showing one hand strap in a lowered position;

FIG. 9 is a front and left side view of a handbag showing a second embodiment of my new ornamental design;

FIG. 10 is a front view thereof;

FIG. 11 is a rear view thereof;

FIG. 12 is a left side view thereof;

FIG. 13 is a right side view thereof;

FIG. 14 is a top plan view thereof;

FIG. 15 is a bottom plan view thereof;

FIG. 16 is a front view thereof showing one hand strap in a lowered position;

FIG. 17 is a front and left side view of a handbag showing a third embodiment of my new ornamental design;

FIG. 18 is a front view thereof;

FIG. 19 is a rear view thereof;

FIG. 20 is a left side view thereof;

FIG. 21 is a right side view thereof;

FIG. 22 is a top plan view thereof;

FIG. 23 is a bottom plan view thereof; and,

FIG. 24 is a front view thereof showing one hand strap in a lowered position.

The broken lines in the figures depict portions of the article and form no part of the claim.

1 Claim, 24 Drawing Sheets
